US0D1105421S

(12) **United States Design Patent** (10) Patent No.: **US D1,105,421 S**
(45) Date of Patent: ** Dec. 9, 2025

(54) **SECUREMENT DEVICE ASSEMBLY
COMPONENT**

(71) Applicant: **Medline Industries, LP**, Northfield, IL
(US)

(72) Inventors: **Saul Godinez**, Chicago, IL (US);
Michael Turturro, Arlington Heights,
IL (US); **Darin Decker**, Chicago, IL
(US); **Karen Daunov**, Chicago, IL
(US); **Greg Corey**, Evanston, IL (US);
Derek Roberts, Boston, MA (US)

(73) Assignee: **Medline Industries, LP**, Northfield, IL
(US)

(**) Term: **15 Years**

(21) Appl. No.: **29/901,117**

(22) Filed: **Aug. 29, 2023**

Related U.S. Application Data

(60) Continuation of application No. 29/739,867, filed on Jun. 30, 2020, now Pat. No. Des. 1,002,006, which is a division of application No. 29/606,291, filed on Jun. 2, 2017, now Pat. No. Des. 890,924.

(57) **CLAIM**

The ornamental design for a securement device assembly component, as shown and described.

DESCRIPTION

FIG. 1 is a top perspective view of a securement device assembly component according to our new design;
FIG. 2 is a bottom perspective view thereof;
FIG. 3 is a top plan view thereof;
FIG. 4 is a right side elevation view thereof, the left side elevation view being a mirror image thereof;
FIG. 5 is a front elevation view thereof;
FIG. 6 is a rear elevation view thereof; and,
FIG. 7 is a bottom plan view thereof.

(Continued)

The broken lines show portions of the securement device assembly component that form no part of the claimed design.

1 Claim, 7 Drawing Sheets
